SAFETY DEVICE FOR PRESSES

Paul N. Shaw, Shaker Heights, Ohio

Application March 15, 1945, Serial No. 582,899

11 Claims. (CL. 74—615)

1

This invention relates generally to safety devices, but has reference more particularly to safety devices which are especially adapted for use in connection with punch presses and the like.

In devices of the general character to which this invention relates, as exemplified in Possons Patent No. 1,417,346, means are provided whereby the hands of a press operator are withdrawn from engagement with the press in timed relation to the movements of the press punch or ram.

It has been found desirable, in connection with various types of press work, to provide means whereby the operator is permitted a greater period of time for the removal of work from the press and for the placement of work in the press than is permitted by the mechanism shown and described in the aforesaid Possons patent, and the present invention, accordingly, is concerned primarily with the provision of such means.

Another object of the invention is to provide a safety device for pulling a press operator's hands away from the press, in which is incorporated means for delaying the operation of such pull-back means, whereby the operator is permitted additional time for the removal of work from the press and for the placement of the work in the press.

A further object of the invention is to provide a device of the character described, which is particularly effective and desirable for use in connection with presses having a long stroke, such as those used for making munition shells and similar articles.

A still further object of the invention is to provide a device of the character described, in which means are incorporated for varying the point in the ram stroke at which the pull-back means becomes ineffective.

Other objects and advantages of the invention will be apparent during the course of the following description.

In the accompanying drawings, forming a part of this specification, and in which like numerals are employed to designate like parts throughout the same,

Fig. 1 is a side elevational view, showing a straight side press, having associated therewith a safety device of the character described, having incorporated therein the novel features of the present invention;

Fig. 2 is a view showing a portion of the mechanism of Fig. 1, on an enlarged scale;

Fig. 3 is a cross-sectional view, taken on the line 3—3 of Fig. 2;

Fig. 4 is a fragmentary side elevation of a portion of Fig. 3;

Fig. 5 is a cross-sectional view, taken on the line 5—5 of Fig. 3;

Fig. 6 is a cross-sectional view, taken on the line 6—6 of Fig. 3;

2

Fig. 7 is a cross-sectional view, taken on the line 7—7 of Fig. 3;

Fig. 8 is a view similar to Fig. 2, but showing a modified form of the invention;

Fig. 9 is a view of a portion of the mechanism of Fig. 8, as viewed from the right of Fig. 8;

Fig. 10 is a cross-sectional view, taken on the line 10—10 of Fig. 9;

Fig. 11 is a cross-sectional view, taken on the line 11—11 of Fig. 10;

Fig. 12 is a cross-sectional view, taken on the line 12—12 of Fig. 10;

Fig. 13 is a cross-sectional view, taken on the line 13—13 of Fig. 10, and

Fig. 14 is a fragmentary elevation of a portion of Fig. 10, as viewed from the left of the Fig. 10.

Referring more particularly to Figs. 1 to 7 inclusive, it will be seen that a conventional punch press, for which the present device is adapted, comprises a stationary base 1, having a bed or work table 2, on which the work is placed, and the usual reciprocating punch or ram 3, the press being provided, as is generally the case, with a flywheel 4. The reciprocatory movement of the ram 3 is provided for by a crank-arm (not shown).

The safety device, in this case, is supported by a pipe 5 which may be connected to the ceiling of the room in which the press is located, and a pair of tie rods 6, which are connected at one end to the base 1 of the press, and at their other end to a coupling 7, which is supported by the pipe 5.

Clamped to the tie-rods 6, adjacent the base 35 of the press is a bracket 8, having rigidly secured therein a cam shaft 9, on the central portion of which is journaled a sleeve 10, to which is keyed a gear 11. The gear 11 is operatively connected to a cam 12 which is also journaled on the shaft 9, the connection being such that rotation of the gear 11 in either direction causes a corresponding movement of the cam 12 about the shaft 9.

The cam 12 has mounted on an extension thereof a non-rotating sheave 13 to which one end of a cable 14 is secured, the cable passing about the cam 12 and about a second sheave 15, which is rotatably supported on the tie-rods 6. The opposite end of the cable is connected to a 50 vertically slidably clip 16, to which are connected a pair of flexible members 14', to the ends of which are connected hand straps 17, which are adapted to be fitted to the hands of the operator.

The cable 14 is normally under such tension as 55 to urge the cam 12 to its rearmost position, as viewed in Fig. 1, and such tension is effected by means of a tension coil spring 16', the ends of which are connected to the clip 16 and to a bracket 17', which extends from the pipe 5.

The bracket 8 has slidably mounted therein for

reciprocal movement a gear-rack 18, which is in mesh with the gear 11.

The rack 18 is operatively connected to the ram 3 of the press in a manner to be presently described, but it may be noted at this point that the connection is such that as the ram descends, its downward movement is communicated to the rack 18, causing the gear 11 to be rotated in a counterclockwise direction, as viewed in Fig. 1, which, in turn, causes the cam 12 to be rocked in a counterclockwise direction about the shaft 9. This causes a pull to be exerted on the cable 14, causing the hands of the operator to be pulled away from the press by means of the hand straps 17, and insuring that the operator's hands will not in any way be injured by the ram or work.

In order to permit the operator a greater period of time for the removal of work from the press and for the placement of work in the press, I have provided a novel operative connection between the rack 18 and the ram 3 of the press, which connection will now be described in detail.

Such connection comprises a tubular housing 19 having a clevis 20 rigidly connected to and closing the upper end of the housing 19, such clevis being connected, as by a pin 21 to the lower flat end 18a of the rack 18.

The housing 19 is provided with elongated slots 22 in opposite sides of the wall thereof, these slots forming slideways for stop pins 23 which extend from a rod 24, adjacent the upper end of said rod. The rod 24 is slidably mounted in a bronze bushing 25 which is pinned or otherwise secured within the housing 19 adjacent its lower end.

The rod 24 has secured to its lower end, as by means of a coupling 26, an extension pipe 27, to the lower end of which a sleeve 28 is connected. The pipe 27 has slidably mounted therein an extension rod 29, to the lower end of which a clevis 30 is secured. The clevis 30 is pivotally secured, as by a pin 31, to a post 32, which extends from the ram 3, adjacent the lower end of the latter.

The rod 29 is provided with a multiplicity of uniformly spaced holes 33, which are adapted to register with pairs of spaced holes 34 in the sleeve 28, a pair of cotter keys 35 being provided, which are adapted for insertion through the aligned holes in the sleeve 28, and rod 29, after the rod has been adjusted relatively to the sleeve 28. The purpose of this adjustment is to vary the effective length of the connection between the pins 21 and 31, depending upon the height of the press or stroke of the ram.

Having thus described the novel connection between the rack 18 and the ram of the press, the operation of the connection will now briefly be described.

When the ram 3 is in its uppermost position, the pins 23 are disposed adjacent the upper ends of the slots 22 in the housing 19. As the ram descends, the rod 24 will be caused to slide downwardly in the housing 19, but the movement of the rod will not be communicated to the housing or to the rack 18, since the pins 23 will merely slide downwardly in the slots 22 for the full length of these slots.

This delay in movement of the housing 19 and rack 18 affords the operator a desired time interval for properly arranging the work on the bed of the press, while, at the same time, the operation of the press is speeded up, since the ram can begin its downward movement, even though the safety device is not effective, during such initial downward movement of the ram, to withdraw the hands of the operator.

When the pins 23 reach the lower end of the slots 22, they come into engagement with the housing 19, and thereafter, with continued downward movement of the ram, the housing 19 is effective to move the rack 18 downwardly and thereby operate the safety device in the manner previously described to withdraw the hands of the operator from the press.

When the ram begins its upward movement, the tension of the spring 16 is effective to cause the rack 18, housing 19 and rod 24 to move upwardly as a unit, with the result that the hand straps 17 are free to move forwardly immediately upon the inception of such upward movement of the ram. This affords the operator additional time to pick up and properly place the new piece of work in the press, and is an additional factor which permits the operation of the press to be speeded up.

The upward movement of the rack 18 is stopped at any desired point by means of a stop collar 36, which is secured, as by set-screws 37, to the rack 18, and which abuts the bracket 8 to determine the extent of upward movement of said rack.

While the aforesaid delayed action ram connection rod is useful for various types of presses, it is particularly effective and desirable for use in connection with presses having a long stroke, such as those used for making munition shells, and similar articles.

Referring more particularly to Figs. 8 to 14 inclusive, these figures illustrate a modified form of delayed-action ram connection rod, with which is incorporated a trip release, the function of which will be presently described.

The delayed-action connection in this case, comprises a tubular housing 40 having a clevis 41 rigidly connected to and closing the upper end of the housing, such clevis being connected, as by a pin 42 to the lower flat end 18a of the rack 18.

The housing 40 is provided at one side thereof with an elongated slot 43, which extends longitudinally of the housing, and has formed in the opposite side thereof a series of longitudinally-spaced, transversely extending recesses 44, which are uniformly spaced along the housing.

Mounted for sliding movement along the housing 40 is a trip release head 45, which may be locked at any adjusted position along the housing which corresponds to the spacing of the recesses 44, by extending a lock-screw 46 through the head and through one of the recesses 44. To facilitate locking of the head to the housing, the head is split as at 47, and the screw is threadedly secured to one of the split sections to enable the head to be clamped to the housing in its adjusted position.

Pivotedly secured to the head 45, as at 48, is a lever 49 having a bracket 50 extending therefrom in one direction, and arms 51 and 52 extending therefrom in the opposite direction. The lever is further provided with a downwardly extending portion 53, to which a trip release dog 54 is secured, as by means of a nut 55, the dog 54 normally extending through the slot 43 and into the space within the housing. The dog 54 has an inclined upper surface 56.

For the purpose of maintaining the dog 54 in its normal position as shown in Fig. 10, a pair of tension springs 57 is provided, these springs interconnecting the arms 51 and 52 of the lever 49 with a pin 58, which extends from the head 45.

A pull-rod 59 is slidably mounted for recip-

rocal movement in the housing 40, bronze bushings 60 being provided to facilitate such movement. Secured to the upper end of the rod 59 is an extension member 61 of reduced diameter, having a head 62 of substantially the same diameter as the pull rod and having its lower face cut away to provide a conical surface 63, the angle of which corresponds to the inclination of the surface 56 of the dog 54.

The pull-rod 59 corresponds to the rod 24 of the previously-described form of the invention, and has secured to its lower end a sleeve 64, in which is slidably mounted an extension rod 65, to the lower end of which a clevis 66 is secured. The clevis 66 is pivotally secured, as by a pin 31, to a post 32, which extends from the ram 3 adjacent the lower end of the latter.

The rod 65 is provided with a multiplicity of uniformly spaced holes 67, which are adapted to register with pairs of spaced holes 68 in the sleeve 64, a pair of cotter keys 69 being provided, which are adapted for insertion through the aligned holes in the sleeve 64 and rod 65 after the rod has been adjusted relatively to the sleeve 64. The purpose of this adjustment is to vary the effective length of the connection rod between the pins 42 and 31, depending upon the height of the press or stroke of the ram.

Trip release mechanism is provided, which comprises a chain 70, which is connected at one end to the bracket 50, as by means of a pin 71, and is connected, as by a pin 72 to the lower end of a rod 73. The rod 73 is secured in any desired position of adjustment in a collar 74, as by means of a set screw 75, the collar 74 extending from a collar or bracket 76, which is clamped to one of the tie-rods 6, as by means of a set screw 77.

Having thus described the modified form of connection between the rack 18 and the ram of the press, the operation of the connection will now be briefly described.

When the ram is in its uppermost position, the various parts of the above-described mechanism will be disposed in approximately the position shown in Fig. 8. As the ram descends, the rod 59 will be pulled downwardly, but there will be no lost motion between such rod and the housing 40, since the head 62 of the extension 61 of the rod engages the dog 50, causing the rod and housing to descend as a unit. Consequently the operator's hands will be pulled back from the press and out of the danger zone during the initial downward movement of the ram.

When the ram has descended to a predetermined point, which is a point at which the chain 70 becomes taut, the lever 49 will be rocked in a counterclockwise direction, as viewed in Fig. 8, about its pivots 48 and against the tension of the springs 57, thereby withdrawing the dog 54 from engagement with the head 62 of the extension 61 of the rod 59. Thereafter, the rod 59 will continue to move downwardly with the ram, and during such movement, the housing 40 will be returned to its initial position by the spring 16', so that no pull is exerted on the operator's hands.

During this period, therefore, the operator's hands are free to approach the press and are in readiness to remove the work piece from the press as soon as the latter has been released by the ram.

During substantially the entire upward movement of the ram, the operator's hands are free to take the work out of the press and to place

a new work piece in the press. Near the end of such upward movement, the head 62 strikes the dog 54 and cams the latter away from the housing 40, so as to permit said head to pass the dog 54 and return to its initial position.

The angle of the surfaces 56 and 63 of the dog and head respectively is such as to preclude any tendency, during the downward movement of the head to rock the release lever 49 about its pivots.

By adjusting the head 45 to various positions along the housing 40, the point at which the release of the rod 59 occurs may be varied to suit various conditions. It is further noted that when the head 45 is in its lower positions, a considerable degree of lost motion between the housing 40 and rod 59 is provided before the head 62 reaches the dog 54 on the downward stroke of the ram. This provides a delayed action of the pull straps at the beginning of the ram stroke, which is desirable for certain types of work, and which is similar to the delayed action described in connection with the first form of the invention.

It is to be understood that the forms of my invention herewith shown and described, are to be taken as preferred examples of the same, and that various changes in the shape, size and arrangement of parts may be resorted to, without departing from the spirit of my invention, or the scope of the subjoined claims.

Having thus described my invention, I claim:

1. In combination with a press having a ram, means responsive to the operative stroke of the ram for pulling the press operator's hands away from the press, and means for delaying the operation of said pull-back means, said delaying means comprising a tubular housing operatively connected to said pull-back means and a rod operatively connected to said ram, and having a lost-motion connection to said housing.

2. In combination with a press having a ram, means responsive to the operative stroke of the ram for pulling the press operator's hands away from the press, and means for delaying the operation of said pull-back means, said delaying means comprising a tubular housing operatively connected to said pull-back means and a rod slidably mounted in said housing and operatively connected to said ram, said rod having a lost-motion connection to said housing.

3. In combination with a press having a ram, means responsive to the operative stroke of the ram for pulling the press operator's hands away from the press, and means for delaying the operation of said pull-back means, said delaying means comprising a tubular housing having elongated slots in opposite walls thereof, and a rod slidably mounted in said housing and having pins extending into said slots.

4. In combination with a press having a ram, means responsive to the operative stroke of said ram for pulling the operator's hands away from the press, said means comprising a tubular housing, a rod slidably mounted in said housing, and a dog maintaining said housing and rod in interlocked engagement, and means for releasing said dog during said stroke of the ram.

5. In combination with a press having a ram, means responsive to the operative stroke of said ram for pulling the press operator's hands away from the press, said means comprising a tubular housing, a rod mounted for slidable movement in said housing, a head adjustably mounted on

said housing, a dog mounted for pivotal movement relatively to said housing, and spring means urging said dog into interlocked engagement with said rod, and means for releasing said dog from said rod at a predetermined point during said stroke of the ram to thereafter permit said rod to descend with the ram independently of said housing.

6. In combination with a press having a ram, and means responsive to the operative stroke of said ram for pulling the press operator's hands away from the press, said means comprising a tubular housing, a rod mounted for slidable movement in said housing, a head rigidly secured to said housing, and a dog mounted for pivotal movement relatively to said housing, said dog being normally interlocked with said rod, whereby downward movement of the rod exerts a direct downward pull on said housing.

7. In combination with a press having a ram, and means responsive to the operative stroke of said ram for pulling the press operator's hands away from the press, said means comprising a tubular housing, a rod mounted for slidable movement in said housing, a head rigidly secured to said housing, a dog mounted for pivotal movement relatively to said housing, and spring means normally maintaining said dog in interlocked engagement with said rod, whereby downward movement of the rod exerts a direct downward pull on said housing.

8. In combination with a press having a ram, and means responsive to the operative stroke of said ram for pulling the press operator's hands away from the press, said means comprising a tubular housing, a rod mounted for slidable movement in said housing, a head rigidly secured to said housing, a dog pivotally mounted on said

housing, said dog being normally interlocked with said rod, whereby downward movement of the rod exerts a direct downward pull on said housing, said head being adjustable along said housing.

9. In combination with a press having a ram, means responsive to the operative stroke of the ram for pulling the press operator's hands away from the press, said means comprising members normally interlocked with each other for movement as a unit, and a dog for maintaining said members in interlocked engagement, and means for releasing said dog at a predetermined point during said stroke of the ram, whereby one of said members may move relatively to the other member during the remaining portion of said stroke of said ram.

10. The combination, as defined in claim 9, in which said releasing means comprises a flexible element having one end thereof operatively connected to said dog.

11. The combination, as defined in claim 9, in which said releasing means comprises a chain having one end thereof operatively connected to said dog.

PAUL N. SHAW.
